UNITED STATES PATENT OFFICE.

PAUL BUTLER, OF LOWELL, MASSACHUSETTS.

CARTRIDGE-SHELL-GAGING MACHINE.

SPECIFICATION forming part of Letters Patent No. 708,123, dated September 2, 1902.

Application filed April 26, 1897. Serial No. 633,902. (No model.)

To all whom it may concern:

Be it known that I, PAUL BUTLER, of Lowell, county of Middlesex, State of Massachusetts, have invented an Improvement in Cartridge-Shell-Gaging Machines, of which the following description, in connection with the accompanying drawings, is a specification, like letters on the drawings representing like parts.

10 The present invention relates to a gaging or assorting machine for cartridge-shells or analogous articles, and is adapted to operate upon such articles when presented to it to separate and assort them according to the 15 shape or dimensions thereof or of a certain part thereof and to collect together those which are of a given predetermined size or shape apart from those which differ therefrom, and the operation is capable of being 20 extended to an indefinite number of classes or sizes, the articles of each class being collected together and separated from the articles of all other classes.

The machine embodying the present invention is especially intended for use with cartridge-shells, the shape and dimensions of which must be of a certain standard in order to fit the breech-chambers of the guns with which they are intended to be used, and the 30 object of the machine is to separate those shells in which a certain part is of a standard size and shape from those in which the same part differs in any respect from the standard, the machine being adapted to collect together 35 the standard shells in one place and also, preferably, to separate and classify those which differ from the standard and collect those of each class by themselves.

In another application, filed April 26, 1897, 40 Serial No. 633,901, I have shown and described a gaging-machine having a similar object—viz., that of gaging and assorting cartridge-shells—the said machine operating to assort said shells according to the thickness of the 45 flanges thereof—i. e., to separate and collect those having flanges of standard thickness from those having flanges of thickness greater or less than standard. The machine of the present invention embodies some of the combinations of said prior machine; and the present invention consists, mainly, in appliances 50 for assorting the shells according to the diam-

eter of the flanged ends thereof to separate those which are not of standard diameter from those which are; and it further consists in 55 novel feed mechanism and in various combinations that will be hereinafter specified.

The machine embodying the present invention is provided with a gage-opening adapted to allow a shell having a flange of standard 60 diameter to pass through when presented to it endwise, but to exclude a shell in which the diameter of the flange is greater than standard and arrest the said shell at the opening of said passage. Thus a shell of standard size or smaller than standard size properly presented to said opening and operated upon by suitable instrumentalities, as will be described, will pass through the same, and a second gage-passage is provided to which are 65 presented shells which have passed through the first gage-passage, and the said second gage-passage is adapted to arrest a shell of standard size, but to allow one of less than standard size to pass through it. Thus shells 70 presented to the machine will, if larger than standard, be arrested at the mouth of the first gage-passage, if of standard size will pass through and beyond said first gage-passage and be arrested at the mouth of the second, 75 and if of less than standard size will pass through both gage-passages to still a different position, so that the shells will thus be separated into three classes, it being obvious, moreover, that by increasing the number of gage- 80 passages the assorting operation might be carried to an indefinite number of classifications. The shells thus presented to the gage-passages are operated upon by a feeler having a yielding actuator, as a spring or gravitation, said 85 90 feeler tending to move them toward said gage-passages, but adapted to be stopped if resistance is offered to its movement, so that as each is presented to the foremost gage-opening it will be engaged by said feeler, 95 which follows said shell until it is stopped by one or the other of the gage-passages or passed completely through both and controls subsequent operations of the machine in accordance with the position in which it is thus 100 stopped. Ejecting devices are also provided, there being a separate ejecting device at each position which can be assumed by a shell adapted to operate after the shell has been

positioned by the gages, and said ejecting devices are so arranged that each one operates to eject a shell so that it will fall in a different position from those ejected by the 5 other devices.

While the operation of the machine to gage and assort the shells as above described is not dependent upon any particular means for presenting the shells thereto, a device for 10 automatically feeding the said shells from a promiscuous mass is preferably provided, the generic features of the feeding device herein shown being similar to those of the feeding device described in my other application 15 above named, said device, however, having certain novel features which form part of the present invention.

Figure 1 is an elevation of a machine embodying the present invention, showing what 20 for convenience will be called the "right-hand side" of the machine; Fig. 2, a similar elevation on a plane at right angles to Fig. 1—i. e., a front elevation; Fig. 3, an elevation of the left-hand side, part of the frame- 25 work being broken away to better show the operating mechanism; Fig. 4, an enlarged horizontal sectional detail on line x^4 of Fig. 3 looking down, showing the shell-carriage in plan; Fig. 5, a similar horizontal sectional 30 detail on the line x^5 , Fig. 3; Fig. 6, an enlarged detail showing the gaging and ejecting devices in elevation with portions of the framework in section; Fig. 7, a view showing a longitudinal section through the axis 35 of the gage-passages; Fig. 8, an enlarged front elevation of the portion of the machine shown in Fig. 6; Fig. 9, a top plan view of the overturning device forming part of the feed mechanism, the parts of the machine 40 above and below said device not being shown; Fig. 10, a side elevation of the same, and Figs. 11 and 12 details which will be herein- 45 after referred to.

In the operation of the machine the shells 45 are presented one by one, with the head or flanged end down, at the opening of a gage- 50 passage a , herein shown as a circular opening in a disk a^2 , as best shown in Fig. 7, secured in any suitable way to a bracket A^3 , 55 supported on a base-plate A^2 at the top of the post A. As herein shown, the said gage-disk is secured to said bracket by means of a metal strap a^3 , Fig. 2, extending around the periphery of the gage-disk and fastened to the 60 bracket by a bolt a^4 and nut a^5 . The said gage-passage a is substantially equal in size to the size of the flanged end of the standard shell, so that such a shell, when presented thereto may be passed through said passage, 65 while if it is larger than standard size it will be stopped at the mouth of the same, where it will remain during one complete operation of the machine. If, however, the shell is of standard size and capable of passing through 70 said gage-passage a , it will be presented to a similar gage-passage b in line with passage a , the said passage b being somewhat smaller

than the flanged end of a standard shell, so that a standard shell will be stopped at the mouth of said passage, while one smaller than 70 the standard will pass through the same to the level of the base-plate A^2 . The passage b is formed in a disk b^2 , secured by metal strap b^3 , bolt b^4 , and nut b^5 to the bracket a^3 , being similar in these respects to the gage-passage a 75 above described. In order to prevent the shells thus presented to the gage-passages from falling through the same by gravity, which might result in their not being properly positioned with relation to the said passages, a reciprocating support or pedestal d is shown as being longitudinally movable through said gage-passages, the movement thereof being so timed 80 with relation to the other parts of the machine that the said pedestal stands, when a shell is presented, in the position shown in Fig. 7, so as to support the said shell at the mouth of the gage-passage a . After the shell is thus presented the said pedestal d moves downward and the shell supported thereon, 85 if small enough to pass through either or both gage-passages, follows the said pedestal, there being also provided a follower or feeler d^2 , movable with the said pedestal, the said feeler having a tapered end adapted to enter the 90 mouth of the shell and center the same with relation to the gage-passage and insure its movement through the said gage-passage, provided it is of the proper size to pass through. The said reciprocating pedestal is positively 95 actuated in its upward movement or movement toward the mouth of the gage-passage a by means of a cam d^3 , carried on the main shaft B of the machine, its downward movement, however, being non-positive and due, 100 for example, to gravitation, assisted, if necessary, by the force of a spring, herein shown as an elastic band d^4 , connected at one end to an arm d^5 , secured to the post A, and at its opposite end to an arm d^6 , with which the 105 reciprocating pedestal d is connected.

The pedestal and feeler are preferably mounted, respectively, upon the arm d^6 and a similar arm d^7 , both connected to a rod d^8 , having a bearing in the base-plate A^2 , which 110 thus forms a guide for the said pedestal and follower, which move in unison. Thus when a shell is presented at the mouth of the passage a it is supported upon the said pedestal, while if the said shell is not properly centered, 115 and therefore does not follow the pedestal by gravity, it is engaged by the feeler d^2 , which thus exerts a slight pressure upon the shell to press it downward, but is supported thereby if the flange is too large to readily enter the 120 gage-passage. The feeler and pedestal are thus supported by the shell during the further operation of the machine until again lifted by the cam to their normal position, thus leaving the shell in position determined 125 by the size of its flange with relation to the size of the gage-passages. The said pedestal and feeler also coöperate with ejecting devices for shells which stop at the mouths of

either of the passages *a* and *b*, as will be hereinafter described.

The shells are presented to the gage-passage *a* by means of a reciprocating carriage *e*, having at one end a pair of jaws *e*³, adapted to move to and from the gage-opening *a*, the shells being fed to the said carriage when in one position, as from a chute *f*, and moved forward thereby to a position over the opening *a*, the movement of the carriage being so timed with relation to the movement of the pedestal *d* as to present a shell over the opening *a* when the said pedestal is at its highest position.

To cause the reciprocating movement of the carriage *e*, the said carriage is connected by a projection *e*⁸ with a lever-arm *e*⁴, having an elongated opening *e*⁵, into which the said projection *e*⁸ extends, said arm *e*⁴ being mounted upon a rock-shaft *e*⁶, Fig. 3, having a bearing *A*⁴ on the base-plate *A*². The said rock-shaft in turn is connected by a lever-arm *e*⁷ and pitman *e*⁸ to a wrist-pin on a disk *e*⁹ on the main shaft *B*, which is rotated, as by a pulley *B*², in the direction of the arrow, Fig. 1, thus causing at each complete rotation of the pulley *B*² a complete forward-and-backward movement of the carriage *e*. The said carriage may be mounted or supported in any suitable way, being herein shown as traveling in a track or guideway *A*⁵, Fig. 4, formed in the standard *A*⁶, which is mounted upon the base-plate *A*².

After the shells have been presented to the gage-passage and are properly positioned with relation thereto according to the sizes of their flanges it is necessary that they should be ejected to make way for the next operation of the machine, the machine being provided with a separate chute or receptacle for shells ejected from each of said positions.

In order to coöperate properly with the other instrumentalities which operate to position the shell presented to the machine, a different ejecting device is arranged to operate at each position which may be assumed by a shell, and the said ejecting devices will be described in order and their relation to the other portions of the machine individually pointed out, it being understood, however, that the invention is not limited to the specific construction shown and described, since modifications might obviously be made without departing from the invention.

Assuming first that a shell presented at the gage-opening *a* is of greater than standard size, so that it will stop at the mouth of said opening, it will be engaged by the downward movement of the feeler *d*², the said feeler entering the mouth of the shell and holding it in position while the carriage recedes, and in order that the said shell may be ejected at the proper time or before another shell is presented an ejector *e*¹⁰, Fig. 4, is provided, consisting of a yielding gate or spring extending across the mouth of the jaws *e*² in the said carriage in front of a shell contained in the

said jaws, the said spring yielding to the shell held by the feeler *d*² during the backward movement of the carriage, but operating to push the said shell before it as the carriage moves forward. As has been stated, the feeler *d*² is so timed with relation to the movement of the carriage that it will be in its uppermost position substantially at the time when the said carriage reaches its extreme forward position, so that the shell will no longer be engaged by the said feeler and will be ejected into a suitable chute *L* and directed thereby to a receptacle, while the shell which has been received from the feeding device at the previous rearward movement of the carriage is then presented to the gage-opening *a*.

The cam *d*³, as shown in Figs. 1 and 3, has a steep incline toward the rear with relation to its direction of rotation, and the cam is so related to the carriage-actuating means that the said steep incline comes under the frame bearing the pedestal and follower just as the carriage reaches its extreme forward position. The follower *d*² thus falls suddenly and engages the shell before the backward movement of the carriage begins, preventing the shell from being withdrawn thereby and forcing the ejector-spring *e*¹⁰ to yield before it in the backward movement of the carriage.

To eject standard shells or those which pass through the passage *a* and stand at the mouth of the passage *b*, a spring-plunger *g* is utilized, said plunger being shown as carried by a slide *g*², longitudinally movable in a guideway *g*³, Fig. 7, in the bracket *A*³ and actuated in a direction to eject the shell by a spring *g*⁴, connected at one end to said bracket and at the opposite end to said spring-plunger. The said plunger is retained in its guideway *g*³ in any suitable way, as by a pin *g*⁵, extending into a slot *g*⁶, Fig. 5, in the guide portion of the plunger. The said plunger coöperates with the pedestal *d*, having an inclined surface *g*⁶, adapted to be engaged during the upward movement of said pedestal, which carries it back to a position ready to operate, or, in other words, "sets" it, and in order to retain it set an arm or holder *g*⁷, Fig. 5, mounted on a pivot *g*⁸, is moved to a position in front of the said plunger *g*, the movement of said arm *g*⁷ being provided for in any suitable way, as by a double cam *g*⁹, coöperating with the arm *e*⁴, which actuates the carriage *e*. The said holder also constitutes a guide for the shells which pass through the passage *a*, the end *g*¹⁰ thereof being, as shown, convex or semicylindrical, embracing the shell and preventing it from falling out.

As shown in Fig. 5, the arm *g*⁷ is thrown into engagement with the plunger *g* by the engagement of the arm *e*⁴ with the cam-surface *g*⁹¹, which occurs just before the carriage reaches its forward position, and remains there until actuated in the opposite direction by the engagement of the arm *e*⁴ with the cam-surface *g*⁹²; such engagement occurring

when the carriage e has nearly reached its extreme backward position. As the carriage recedes, therefore, and the pedestal d travels downward the plunger g will be retained set 5 by the arm g^7 , and the shell following, if of standard size, will be stopped at the mouth of the opening b , while the feeler d^2 , extending into the said shell, will retain it against lateral displacement until said feeler is re- 10 moved by the upward movement caused by its actuating-cam, as above described. Thus when the carriage has reached or nearly reached its extreme rear position the arm g^7 will be removed from the path of the plunger g , the said plunger thus being held by the shell itself, which in turn is held by the feeler d^2 , and in the further movement of the machine the said feeler will be raised by its actuating-cam until it passes out of the 15 mouth of the shell, there then being nothing to retain the plunger g in its said position, so that it will move sharply forward in response to the spring g^1 and eject the shell into the chute S , Fig. 1, said chute being preferably 20 provided with a guard S^2 near its upper end to prevent the shell from being thrown beyond the pathway afforded thereby. A shell which is smaller than standard will pass completely through the passages a and b , remain- 25 ing on the pedestal d until the latter reaches its lowermost position, in which the end or supporting portion thereof is substantially on a level with the base-plate A^2 . The shape of the actuating-cam d^3 is such that the pedestal 30 d will dwell for an instant in its lowermost position, and during this dwell the shell standing below the passage b will be struck a blow by an ejector-finger h , pivoted at h^2 , Figs. 2 and 3, upon the post A . To actuate 35 the said ejector-finger h at the proper time, a spring-arm h^3 is shown as carried by the disk e^9 on the main shaft B and adapted during the rotation of said shaft to engage the projection h^4 from the lower end of the 40 ejector-finger h , so as to rock the same on its pivot, causing the upper end thereof to move to the right (see Fig. 3) and eject the shell into the chute T . The projection h^4 from the said ejector-finger and the portion 45 of the pedestal-carrier which engages with the cam d^3 , herein shown as a cam-roll d^{30} , mounted on a projection d^{31} from the arm d^6 , are on the same side of the axis of rotation of the main shaft B , while the engaging portions 50 of the cam d^3 and spring-arm h^3 , respectively, are on the opposite sides of said shaft, so that the arm h^3 will operate the ejector h when the pedestal d is in its lowermost position. Thus a shell larger than standard will be retained 55 at the mouth of the gage-passage a and laterally supported by the feeler d^2 during the rearward movement of the carriage e and ejected by the spring e^{10} during the forward movement of the carriage, which is accomplished by an 60 upward movement of the pedestal and feeler, so that the shell is no longer laterally retained thereby. A shell of standard size will be re- 65

tained at the opening of the passage b , where it is laterally supported by the feeler d^2 , until the latter is actuated in an upward direction 70 by its actuating-cam d^3 , and said shell will be ejected by the spring-plunger g as soon as released by the upward movement of the follower d^2 , the retaining-arm g^7 for said plunger having in the meanwhile been removed 75 from the path thereof by the engagement of the arm e^4 with the cam-surface g^{92} . A shell which is smaller than standard will remain on the surface of the pedestal d until said pedestal reaches its lowermost position, at which 80 time the ejector-arm h will be actuated, striking and ejecting the said shell.

As has been previously stated, the shells are fed to the reciprocating carriage e through a chute f , down which the shells are fed in a 85 column and supported upon the upper surface of the carriage until the opening between the jaws e^2 comes under the said chute, when the lowermost shell will drop between the said jaws and be pushed forward by the forward 90 movement of the said carriage. It is necessary, however, for the proper operation of the machine that the shell should be presented to the carrier head down, and while it is obvious that the shells might be fed in any suitable way to the said chute or directly to the carrier, provided the shells were supplied by 95 said chute or introduced into the carrier with the flanged end down, it is preferable to provide feeding mechanism which shall be entirely automatic and in which the shells may be fed from a promiscuous mass in a hopper and automatically arranged in uniform position before reaching the carrier e , no matter what position they may be in when they first 100 fall into the receiver. For this purpose the feed mechanism also comprises a second chute f^2 , adapted to receive shells from the hopper f^3 , and the shells coming through said chute f^2 are supported upon the upper surface of 105 a traveling receiver, such as the rotating disk f^4 , having along its periphery a series of openings f^5 , each adapted to receive a shell as it passes under the end of the chute f^2 . Underneath the said disk is a support for the 110 shells, shown as a stationary platform f^6 , upon which the shells fed to the openings f^5 rest and along which they travel in the receiver f^4 . Thus a shell passing out from the chute f^2 falls into one of the openings f^5 and is carried along in the direction of the arrow, Fig. 9, until it reaches the mouth of the chute f , which extends upward into or directly beneath an opening in the support or stationary 115 platform f^6 , the mouth of the said chute being indicated at f^7 . As soon as the shells arrive over the said mouth f^7 in the rotation of the disk f^4 they will drop down into the same and be fed through the chute f to the reciprocating carriage e . In order that shells presented to the said rotating disk wrong end up—i. e., with their mouths down—may be inverted so that they will be presented to the chute f head downward, as is necessary, the 120 125 130

stationary platform f^6 is provided with an engaging portion or cam, the nature of which is such as to engage the smaller or mouth end of a shell, but to allow the larger or flanged end of the shell to pass without being engaged, such cam being herein shown as the inner edge f^8 of a groove in the surface of the support, the said edge extending from a point behind the path of travel of a shell when carried forward by the rotating disk to a point near the periphery of the stationary platform. The said groove is somewhat narrower than the diameter of the flanged end of the shell, and when the said shell is presented flange down it will travel across the said groove, owing to the larger diameter of the flanged end, which will reach across the groove and not be engaged or caught by the edge thereof. It is not, however, essential that the said flanged end should absolutely straddle the groove, since the said flanged end is heavier than the open end, so that there is but little tendency for the shell to tip, and the flanged end can project across the groove for a considerable distance without affecting the stability of the shell. Furthermore, the rounded edge of the flanged end will not readily catch the cam, so that a shell presented flanged end down will never be tipped from its vertical position. If, on the other hand, the shell is presented with the open end down, it is obvious that in view of the fact that the closed or flanged end is heavier a very slight lateral movement of the open end, upon which the shell is supported, will cause the shell to tip. As the open end of the shell travels across the groove it will naturally tip slightly into the groove, (being top-heavy,) and a very slight movement will cause the sharp edge to catch the cam f^8 , which will cause a lateral movement of the said lower end toward the periphery of the carrier, which movement, however, will not be imparted to the shell as a whole, since the said shell has already slightly left a vertical position. The lower end of the shell, therefore, will be pushed outward, while the flanged end settles down into the recess, and the shell will soon fall on its side, as indicated in dotted lines, Fig. 9. In order to prevent the shell thus tipped over from passing endwise out of the opening f^5 , the side of said opening toward the periphery of the disk through which the body of the shell projects when tipped is made somewhat narrower than the main portion of the opening, the distance across the said portion being less than the diameter of the flange of the shell. The shell thus tipped downward will be carried along on its side with its outer end projecting out beyond the periphery of the disk f^4 , the said outer end being engaged during the further movement of the said disk by an inclined surface or cam f^9 , rising from the surface of the stationary platform, so that the outer end of the shell will ride up the said inclined surface until the shell is finally tipped up upon its closed or flanged end.

Thus each opening as it passes the chute f^2 receives a shell, and the said shells if presented with their closed ends down are carried forward in that position and if presented with their open ends down are inverted by the engaging portion f^8 and cam f^9 , so that beyond the cam f^9 each recess f^5 contains a shell properly righted or with the flanged end down, and said shells are dropped consecutively into the chute f^2 as the openings f^5 pass the mouth thereof. It is obvious so far as relates to this feature of the invention that other articles might be fed and arranged by substantially the same devices as are herein shown, it being necessary only that the opposite ends of each article should have different characteristics. In other words, any article so shaped that one end thereof will be engaged by the portion f^8 , which practically constitute a cam, while the other end will not be engaged thereby, can be operated upon by this mechanism, so that a number of said articles may be uniformly arranged, although supplied to the carrier either end up. The rotating disk is mounted upon the end of an upright shaft f^{10} , provided at its lower end with a gear f^{12} , Fig. 1, which meshes with a suitable gear f^{13} on a shaft f^{14} , Fig. 3, which is driven by a chain f^{15} , connected with a sprocket on said shaft and a sprocket on the main shaft B, respectively. The said gear f^{13} may be a worm or other suitable gear, the connection being indicated by dotted lines, Fig. 3. The shaft f^{14} is mounted in a bearing A⁷, extending downward from the under surface of the base-plate A². The stationary platform f^6 is mounted at the top of a standard A⁸, mounted on an extension A⁹ on the bracket A⁶, and the shaft f^{10} passes upward through said standard, which forms a bearing therefor. To keep the shells agitated in the hopper, so that they will be continually presented to the chute f^2 , a supplemental chute f^{20} is provided, telescoping with the chute f^2 and having a reciprocating movement within the hopper, the said chute f^{20} being mounted in a guide f^{21} in the upright which supports the hopper f^3 and being connected by a rod f^{22} with the wrist-pin on the rotating disk e^9 upon the shaft B. One or more arms f^{23} are preferably connected with the said chute f^{20} , thus having a reciprocating motion therewith within the hopper. In order to prevent a shell not properly fed to the disk f^4 or the carriage e from catching and clogging the machine, gates f^{16} are shown as pivotally supported at the ends of said chute, adapted to yield before a shell not fully discharged from the chute. These gates are best shown in Figs. 11 and 12 and are pivoted at f^{17} to the body of the chute and provided with springs f^{18} , whereby they are normally maintained closed, the pivotal supports for the gates being so arranged, however, that the gates will open against the stress of their springs in the direction of rotation of the shell-receiver below. It is ob-

vious, therefore, that if a shell is caught by the carrier before it has fully come out of the chute the spring will yield, allowing the gate to open and the shell to pass out laterally. Both chutes, moreover, are provided with longitudinal slots f^{24} , through which a wire may be inserted to disengage a shell if one becomes caught or stuck.

- The operation of the machine is as follows:
- 10 The shells with which the hopper is supplied descend in a column through the chute f^2 and fall into the recesses in the arranging device either end up, as the case may be. Each recess receives one of the shells, and as the arranging device travels those shells which stand upon their open ends are engaged at the bottom and tipped on their sides, as described, the open end then being lifted in the further movement of the arranging device until the shell stands on its flanged end.
  - 15 The shells thus arranged then drop through the chute f and are engaged and pushed forward by the carrier to a position over the line of gage-passages. The shell-support then moves downward in conjunction with the feeler, each shell being arrested at the proper position according to its size, and the several ejecting devices operate as soon as the shell is disengaged by the feeler in the upward
  - 20 movement thereof, so that the shell then in the machine is ejected into the proper chute.
  - 25 It is not intended to limit the invention to the specific construction shown and described, since such construction may obviously be modified without departing from the invention.

What I claim is—

1. In a gaging-machine for cartridge-shells, the combination with a gage-passage adapted 40 to admit articles of a predetermined size or smaller but to exclude articles of a larger size, of a succeeding passage or passages in alignment with said gage-passage each smaller than and independent of the one preceding 45 it, means for positively moving an article toward said series of passages until stopped by one of them, and ejecting devices for ejecting an article standing in any of the positions determined by the gage-passages, substantially as described.

2. The combination with a pair of gage-passages, of a support longitudinally movable therein, a feeler adapted to engage a shell stopped at the mouth of either passage, ejecting devices adapted to operate on said shell when released by said feeler, and connecting mechanism whereby said parts are caused to coöperate, substantially as described.

3. In a gaging-machine for cartridge-shells, 60 the combination with a gage-passage, of a support longitudinally movable through said passage, a feeler movable with said support and adapted to engage a shell which will not pass through said passage, an ejecting device for said shell adapted to operate when the shell is disengaged by the said feeler, and connect-

ing mechanism whereby said parts are caused to coöperate, substantially as described.

4. The combination with the gage-passages and means for presenting a shell thereto, of 70 the means for controlling the movement of the shell with relation to said passages consisting of a supporting-pedestal for the shell movable through said passages, and a feeler movable with said pedestal to engage a shell 75 which will not pass through said passages or either of them, substantially as described.

5. The combination with a gage-passage, of a reciprocating carriage adapted to present a shell thereto, a pedestal to receive and support a shell thus presented, means for moving said pedestal to permit the shell supported thereon to enter said passage, a feeler movable with said pedestal to engage a shell which is too large to enter said passage, and a portion of the carriage adapted to yieldingly engage a shell during the movement of said carriage in the opposite direction, substantially as described.

6. The reciprocating carriage e provided 90 with the jaws e^2 and the ejector-spring e^{10} , combined with the gage-passage α and the feeler d^2 , as and for the purpose described.

7. The combination with the different-sized gage-passages in alignment with each other, 95 of the reciprocating support adapted, when free, to move through said passages away from the openings thereof to which a shell is presented, the feeler movable with said support, and means for positively actuating said 100 support toward said openings, substantially as described.

8. The combination with a gage-passage and means for presenting a shell thereto, of a second gage-passage in line therewith, a 105 support or pedestal movable through said passages, a feeler adapted to engage a shell stopped by either passage, a spring-operated ejecting device for shells stopped by the second passage adapted to be set by said pedestal in its movement in one direction, and means for maintaining it set during the movement thereof in the opposite direction, substantially as described.

9. The combination with a gage-passage 115 and means for presenting a shell thereto, of a second gage-passage in line therewith, a support or pedestal movable through said passages, a feeler adapted to engage a shell stopped by either passage, a spring-operated 120 ejecting device for shells stopped by the second passage adapted to be set by said pedestal in its movement in one direction, an engaging member adapted to maintain said ejector-set until engaged by a shell stopped 125 by the passage and held by the feeler, and means for disengaging said member after the shell is so held, substantially as described.

10. The combination with the gage-passage and the reciprocating carriage for the shells, 130 of the movable support and feeler, an ejecting device comprising a spring-actuated plun-

ger adapted to be set by said movable support, a retaining device for maintaining said plunger set, and an operating-cam for said retaining device coöperating with the reciprocating carriage, substantially as and for the purpose described.

11. The combination of the spring-actuated plunger g having the inclined surface g^6 ; with the pedestal d ; the retaining device g^7 and means for operating the same; and the feeler d^2 , substantially as and for the purpose described.

12. The combination with a reciprocating carriage adapted to receive a shell and present it to a suitable gage-passage, of a movable support for the shell, a cam for positively moving said support to a position to receive a shell presented by the carriage, means for yieldingly producing the return movement of said support, a feeler movable with said support, and actuating mechanism for said carriage and cam whereby the downward movement of the support and feeler takes place substantially when the carriage is in position to present the shell to the gage-passage, substantially as described.

13. In a machine for operating on cartridge-shells, the combination with a feed - chute adapted to receive said articles from a suitable hopper, of a traveling receiver for said articles; cams in the path of a shell carried by said receiver for overturning and righting said shell if presented to said receiver wrong end up while said shell is still in the receiver, and an opening in the path of the shells carried by the said receiver, through which opening said shells are fed to the machine, substantially as described.

14. In a machine for operating on cartridge-shells, the combination with a feed - chute adapted to receive said articles from a suitable hopper, of a traveling receiver for said articles, a cam adapted to engage the mouth of a shell traveling in said receiver and draw it aside until the shell falls on its side without leaving the receiver; and means for righting said fallen shell in the receiver, substantially as described.

15. In a machine for operating on cartridge-shells, the combination with a feed - chute adapted to receive said articles from a suitable hopper, of a traveling receiver for said articles, a cam adapted to engage the mouth of a shell traveling in said receiver and draw it aside until the shell falls on its side in the receiver; an inclined surface beyond said cam adapted to engage the mouth end of a shell during the onward movement of the traveling receiver and lift said end until the shell stands on its flanged end in the receiver, and an opening in the path of shells carried by the traveling receiver through which all of the shells in the receiver are fed to the machine, substantially as described.

16. The combination with the chute f^2 , of the support f^6 provided with an opening f^7 , the traveling receiver f^4 having recesses f^5 ,

the cam f^8 , and the inclined surface f^9 adjacent to the said receiver and in the path of an article carried thereby, substantially as shown and for the purpose described.

17. The combination with a feed - chute adapted to contain a column of shells endwise, with a support for the shells below said chute, means for moving said shells along the surface of said support, a cam in the path of shells thus moved, arranged to engage the mouth of a shell but not the flanged end thereof and inclined to the direction of travel of the shell, whereby the mouth of the shell is drawn from under the center of gravity to tip the shell upon its side, an inclined righting-surface so positioned with relation to the receiver as to be in the path of the shell thus tipped; and an opening in the said support to which the shells are finally carried, substantially as described.

18. The combination with a feed - chute adapted to contain a column of shells endwise, of a traveling shell-receiver below said chute having recesses each adapted to receive and carry along a shell dropped therefrom, a lateral opening in said chute of sufficient size to permit a shell to pass out laterally in the direction of movement of the traveling receiver, and a normally closed gate for said opening arranged to open in response to pressure, whereby a shell caught by the receiver before it has fully emerged from the chute is permitted to escape therefrom without detriment, substantially as described.

19. In a machine for operating on cartridge-shells, the combination with the feed-chute adapted to receive said articles from a suitable hopper, of a traveling receiver for said articles adapted to receive the articles endwise from the feed-chute, a support for the articles along which they are propelled by the receiver, and a cam adapted to engage the end of an article as it is propelled by said receiver and deflect the same until the said article falls from its end upon its side, substantially as described.

20. In a machine for operating on cartridge-shells, a rotating feed-disk having radial recesses, means for presenting articles to said recesses either end uppermost, a support for the articles along which they are carried by said disk, and a cam stationary with relation to said disk and adapted to engage and deflect one end of an article traveling along the support but not the other whereby the articles will remain on end upon the support or be tipped over sidewise upon the support according to the position in which they were originally presented, substantially as described.

21. In a machine for operating on cartridge-shells or other articles the opposite ends of which differ in shape, the combination with a traveling carrier adapted to receive one of such articles in a substantially vertical position, of a support for said article below said carrier, and a cam formed on said support and

so shaped and arranged as to engage and deflect an article traveling along the support on one end but not an article traveling along the support on the other end.

5 22. The combination with a disk having radially-arranged shell-receiving recesses; of means for feeding shells thereto either end up; and cams so arranged with relation to said disk as to coöperate therewith in rearranging 10 the shells after they have been fed thereto to secure a uniform end arrangement thereof in said disk.

15 23. In a machine for operating on articles the longitudinal dimension of which is greater than the lateral dimension, the combination with a traveling receiver adapted to receive one or more of such articles vertically positioned, of a support below the said receiver for said article, a cam or deflecting surface so arranged with relation to said receiver as to engage an article propelled thereby at a point 20 near one end thereof, and means for substantially preventing a lateral movement of the

other end of the article in the same direction while it is engaged by the cam, whereby said article is tipped from a vertical to a horizontal position upon said support, substantially as described. 25

24. In a machine for operating on articles the longitudinal dimension of which is greater than the lateral dimension, the combination with a traveling receiver having laterally-open recesses along its periphery each adapted to contain and forward one of such articles, of means for tipping said articles from a vertical to a horizontal position in the travel of the receiver, and means for preventing the articles thus tipped from escaping endwise from the recesses, substantially as described. 30

35 In testimony whereof I have signed my name to this specification in the presence of two subscribing witnesses.

PAUL BUTLER.
